PAGE 2

FIG - 4

FIG - 6

FIG. 1 is a top plan view of an electric toaster embodying our new design;

FIG. 2 is a front view of the same;

FIG. 3 is a left end view of the same with the horizontally sliding tray partially pulled out, both ends being substantially the same in appearance;

FIG. 4 is a rear view of the same;

FIG. 5 is a bottom plan view of the same; and

FIG. 6 is a three-quarter front perspective view of the same taken from a level higher than its top.

We claim:

The ornamental design for an electric toaster, as shown and described.
